[57] CLAIM

The ornamental design for a child's crawler, as shown and described.

DESCRIPTION

FIG. 1 is a perspective view of a child's crawler showing my new design;

FIG. 2 is a top plan view thereof;

FIG. 3 is a front elevational view thereof;

FIG. 4 is a side elevational view thereof;

FIG. 5 is a rear elevational view thereof;

FIG. 6 is a bottom plan view thereof; and

FIG. 7 is a perspective view of a child's crawler showing a second embodiment of my new design, the sole difference being in the addition of a removable chest wedge and leg abductor wedge.

FIG. 1

FIG. 2

FIG. 3

FIG. 4

FIG. 5

FIG. 6

FIG. 7

Disclaimer and Dedication

Des. 261,378.—Timothy J. Bergeron, Dolgeville, N.Y. CHILD'S CRAWLER. Patent dated Oct. 20, 1981. Disclaimer and Dedication filed May 13, 1985, by the assignee, J. A. Preston Corp.

Hereby disclaims and dedicates to the Public the remaining term of said patent.
